UTILITY CHAIR

William H. Ryan, Los Angeles, Calif.

Application July 6, 1953, Serial No. 25,816

Term of patent 14 years

(Cl. D15—8)

To all whom it may concern:

Be it known that I, William H. Ryan, a citizen of the United States of America and a resident of the city of Los Angeles, in the county of Los Angeles and the State of California, have invented a new, original, and ornamental Design for a Utility Chair, of which the following is a specification, reference being had to the accompanying drawing, forming a part thereof.

In the drawings:

Fig. 1 is a side perspective view of a utility chair, showing my new design.
Fig. 2 is a rear perspective view thereof.

I claim:

The ornamental design for a utility chair, substantially as shown.
